UNITED STATES PATENT OFFICE.

DAVID B. WARREN, OF WEST PLAINS, MISSOURI.

KNOCKDOWN CAMP-STOVE.

SPECIFICATION forming part of Letters Patent No. 657,631, dated September 11, 1900.

Application filed June 16, 1900. Serial No. 20,594. (No model.)

To all whom it may concern:

Be it known that I, DAVID B. WARREN, a citizen of the United States, residing at West Plains, in the county of Howell and State of Missouri, have invented certain new and useful Improvements in Knockdown Camp-Stoves; and I do declare the following to be a full, clear, and exact description of the invention, such as will enable others skilled in the art to which it appertains to make and use the same.

My invention relates to improvements in portable stoves of the camp-stove pattern.

One object of the invention is to provide a stove of this character which is simple in construction, efficient in operation, and adapted to be readily and conveniently "knocked down" or folded for storage and transportation and as readily and conveniently set up for use.

A further object of the invention is to provide a stove in which the parts are slidably fitted together and adapted to be disassembled and packed in flat form, so as to be easily carried or packed away in a minimum amount of space.

With these and other minor objects in view the invention consists of certain novel features of construction, combination, and arrangement of parts, as will be hereinafter more fully described, and particularly pointed out in the appended claim.

In the accompanying drawings, Figure 1 is a perspective view showing the stove set up for use. Fig. 2 is a side elevation looking toward the side of the stove in which the sliding door is mounted. Fig. 3 is a central vertical longitudinal section. Fig. 4 is a horizontal section. Fig. 5 is a cross-section. Fig. 6 is a horizontal section of the flue.

Referring now more particularly to the drawings, in which like reference characters designate corresponding parts throughout the several views, 1 represents the front wall, 2 the back wall, and 3 4 the side walls composing the frame or body of the stove. These parts are slidably fitted together, being provided with corresponding tongue-and-grooved joints 5, by which they may be conveniently assembled and disassembled and packed together flat for storage or transportation. This wall or body is closed at the top by a sliding cover

6 and at the bottom by a sliding bottom piece or wall 7, having tongue-and-grooved connections 3^a with the said side walls 3 and 4, whereby they may be applied and removed in like manner. 55

The interior of the frame or body is subdivided to form a fire-box 8, an oven 9, and top, bottom, and end flues or passages 10, 11, and 12 in communication with each other, and with an opening 13 in the cover 6, through which the smoke and products of combustion from the fire-box discharge into the flue or smoke-pipe 14, and thence to the atmosphere. 60 65 This smoke-pipe, which may be of any desired length and number of sections, of which one is shown in the drawings, is composed of side and end walls 15 and 16, having tongue-and-grooved joints 3^b slidably connecting them, and is detachably connected with the cover 6 by means of flanges 17, projecting from the lower ends of the side walls 15 and adapted to slide beneath the free edges of keeper-strips 18, secured to said cover upon 70 75 opposite sides of the opening 13.

The fire-box 8 is formed between the front, side, top, and bottom walls of the body and a vertical partition 18^a, which latter is provided at its side edges with flanges 19, adapted to 80 engage beneath one of the free edges of each of two vertical keeper-strips 20, centrally secured upon the inner faces of the side walls 3 and 4, so that it may be applied and removed with facility. The oven 9 is arranged 85 in rear of the fire-box and is composed of top and bottom plates 21 and 22 and side plates 23, slidably and detachably connected by tongue-and-grooved joints 3^c. These plates are detachably supported in the casing by 90 brackets 24, secured to the side walls 3 and 4, and on which the bottom plate 22 is adapted to rest, and by flanges 25, projecting from the plates 23 and engaging the adjacent free edges of the keeper-strips 20 and similar keeper-strips 20^a, the latter located in the rear flue-passage 12, formed between the rear walls of the body and oven and sides of the oven. By the above construction and arrangement of parts a vertical flue or passage 12^a is also 95 100 formed between the fire-box and oven and coacts with the passages 10, 11, and 12 to permit of the circulation of the heated air, smoke, and products of combustion entirely around

the oven, whereby rapid and even cooking of the contents thereof is insured.

Access to the interior of the fire-box and oven is afforded through openings 26 and 27 in the side wall 4 of the body. These openings are adapted to be closed by a door 27^a, slidably mounted in grooves or ways formed by guide-strips 28, secured to the outer face of the side 4 along the upper and lower edges of said openings. The door is provided at each end with a finger-piece 29, whereby it may be slid in either direction to close either or both of the door-openings 26 and 27. By moving the door to the right the opening 26 to the fire-box may be exposed without exposing the opening 27 to the oven, and by moving the door to the left the reverse operation may be effected. Access may also be obtained to the fire-box for the purpose of stirring up the fuel through an opening 30 in the front wall 1 of the body, which opening is adapted to be closed by a pivoted door, damper, or valve 31. This opening also serves to admit air into the fire-box to promote combustion, and the pivoted valve or damper permits of the supply being regulated as desired.

The flow of the hot air, smoke, and products of combustion through the passages 10 and 12 is controlled by a damper 32, arranged in front of the opening 13 and between the top sections 6 and 21 of the stove-body and oven and carried by a shaft 33, detachably mounted in the side walls 3 and 4. A crank 35 or other suitable handle 34 is formed upon one end of the shaft for convenience in operating the valve from the exterior.

Pot-holes covered by suitable plates or covers may be provided in the top wall or cover 6 of the body, if desired.

To support the stove when set up for use, legs 35 are provided and consist of strips of metal having their longitudinal edges folded and spread at one end to form keepers to receive the free ends of strips secured transversely to the bottom of the stove, whereby the legs are detachably fitted thereto. The ends of these strips are bent at right angles to form a base 36 to rest on the floor or ground

and a connecting portion 37, in which the keeper is formed.

The drawings show the stove set up for use. To knockdown or fold the stove for storage or transportation, it is simply necessary to slide the parts out of locking engagement, 55 when they may be piled flat on one another and suitably secured together, as will be readily understood. The device is thus adapted to be readily and conveniently set up for use and folded in a minimum amount of space 60 to enable it to be conveniently carried or shipped.

Having thus described my invention, what I claim, and desire to secure by Letters Patent, is—

A portable knockdown camp-stove, comprising in its construction a body formed of front, rear and side walls having tongue-and-grooved joints slidably connecting them, one of said side walls having fire-box and oven 70 openings, top and bottom walls slidably connected to said side walls and closing the top and bottom of the body, a partition removably mounted in the body between said fire-box and oven openings and forming with the 75 front, side and top and bottom walls of the body a fire-box, an oven mounted between said partition and the rear wall of the body and comprising top, bottom and side plates detachably connected and supported, flue-passages being formed in front of and at the 80 rear, top and bottom of the oven, a smoke pipe or flue detachably connected to the sliding top of the body, a damper controlling the passage of the smoke and products of combustion through the bottom and rear flue passages to the pipe, and a door slidably mounted on the side of the body and movable in either direction to control said fire-box and oven openings, substantially as set 90 forth.

In testimony whereof I have hereunto set my hand in presence of two subscribing witnesses.

DAVID B. WARREN.
